(57) **CLAIM**

The ornamental design for an electronic cigarette assembly, as shown and described.

DESCRIPTION

FIG. 1 is a front elevational view of an electronic cigarette showing my new design as a first component removed from the assembly shown in FIGS. 25–32 for clarity of disclosure; FIG. 2 is a rear elevational view thereof; FIG. 3 is a left side elevational view thereof; FIG. 4 is a right side elevational view thereof; FIG. 5 is a top plan view thereof; FIG. 6 is a bottom plan view thereof; FIG. 7 is a front, right, and bottom perspective view thereof; and

FIG. 8 is a rear, left, and top perspective view thereof. FIG. 9 is a front elevational view of an electronic cigarette showing my new design as an alternative first component removed from the assembly shown in FIGS. 25–32 for clarity of disclosure;

FIG. 10 is a rear elevational view thereof; FIG. 11 is a left side elevational view thereof; FIG. 12 is a right side elevational view thereof; FIG. 13 is a top plan view thereof; FIG. 14 is a bottom plan view thereof; FIG. 15 is a front, right, and bottom perspective view thereof; and

FIG. 16 is a rear, left, and top perspective view thereof. FIG. 17 is a front elevational view of an electronic cigarette showing my new design as a second component removed from the assembly shown in FIGS. 25–32 for clarity of disclosure;

FIG. 18 is a rear elevational view thereof; FIG. 19 is a left side elevational view thereof; FIG. 20 is a right side elevational view thereof; FIG. 21 is a top plan view thereof; FIG. 22 is a bottom plan view thereof; FIG. 23 is a front, right, and top perspective view thereof; and

FIG. 24 is a rear, left, and bottom perspective view thereof. FIG. 25 is a front elevational view of the electronic cigarette showing my new design where the first component as shown in FIGS. 1–9 and the second component are shown assembled state of use;

FIG. 26 is a rear elevational view thereof; FIG. 27 is a left side elevational view thereof; FIG. 28 is a right side elevational view thereof;

(Continued)

FIG. 29 is a top plan view thereof;
FIG. 30 is a bottom plan view thereof;
FIG. 31 is a front, right, and top perspective view thereof;
and,
FIG. 32 is a rear, left, and bottom perspective view thereof.
The broken lines in the figures are included for the purpose of illustrating portions of the article which form no part of the claimed design.
